UNITED STATES PATENT OFFICE.

ROY STANLEY ASHTON, OF WASHINGTON, DISTRICT OF COLUMBIA.

MEANS FOR TEACHING SHORTHAND.

1,027,514.

Specification of Letters Patent.

Patented May 28, 1912.

Application filed March 27, 1908. Serial No. 423,677.

To all whom it may concern:

Be it known that I, ROY STANLEY ASHTON, citizen of the United States, residing at Washington, in the District of Columbia, have invented certain new and useful Improvements in Means for Teaching Shorthand, of which the following is a specification.

This invention relates to certain new and useful improvements in devices for use in teaching shorthand, languages, spelling, etc.

The present invention has for its objects among others to provide a simple and cheap device for facilitating the learning of the principles of shorthand for practical use, and it comprises a shield for holding the exercise sheet, and a hinged or movable portion at one end of the shield of proper length and width and adapted to serve as herein-after described.

Other objects and advantages of the invention will hereinafter appear, and the novel features thereof will be particularly pointed out in the appended claims.

The invention in its preferred form is clearly illustrated in the accompanying drawings, which, with the numerals of reference marked thereon, form a part of this invention and in which—

Figure 1 is a view of the copy holder with the hinged portion closed and the exercise card in place. Fig. 2 is a similar view with the hinged part thrown back and a portion of the holder broken away. Fig. 3 is an edge view. Fig. 4 is a view of the exercise card.

Like numerals of reference indicate corresponding parts throughout the several views.

This device consists of paper in sheets (only one of which is shown), ruled with a base line 2 (in red for shorthand use), with intermediate lines 3 in other colors, if desired, to determine the height of letters, also with vertical lines 4 to provide alternate columns of longhand and shorthand, or vice versa; or for one column of longhand alternating with two or three columns of shorthand, or vice versa; or in columns of equal width each of which is to be filled with shorthand; the style of ruling depending upon the method in which the device is used, as hereinafter described, and also upon the character of the exercises to be written. There is also a shield 5 constructed of paper, wood, metal or other substance, open at one or both ends, as at 6, into which the ruled

sheet 1 as above described, fastened with clips 7 to a baseboard 8 of some inflexible material, is inserted and may be pushed in as the sheet is filled column by column, so that the edge of the shield coincides with the left-hand edge of the column in which the writing is being done so as to cover and conceal that portion of the sheet already written upon.

The shield is constructed in the form of a long, flat box, open at one or both ends, into which the exercise sheet, mounted on its baseboard, is inserted as described above. To the top or lid or cover 9 of the shield is attached a copy-holder, which consists of a strip of thin, inflexible material 10, about from three to five inches wide and as long as the shield is wide, to reach from edge to edge of the shield. This strip is hinged at its left hand side, as at 11, to the cover of the shield in such a manner that when turned down the right hand edge of the strip will coincide with the right hand edge of the shield.

The copy is printed or written near the right hand edge of slips ruled to correspond with the ruling on the sheet as described above, the slips to be of convenient width for attaching to the copy-holder as hereinafter described. The shorthand copy may be contained on one slip and the corresponding longhand key on a separate slip, or both the shorthand and the longhand copies may be contained on the same slip in columns side by side, as in Fig. 1, the shorthand copy next to the edge. In the longhand key, to economize space, two or three words may be written or printed one above the other between each base line, the same words to be produced in the shorthand copy side by side on the corresponding base line between the vertical lines defining the column.

The device may be used in different ways, as follows: A copy, consisting of a single slip on which appears both the shorthand copy and the longhand key, as described above, is attached face upward to the copy-holder (hinged portion) by means of clips 12, in such a manner that the right hand edge of the copy will coincide with the right hand edge of the holder. In this position the right hand edges of the copy, the holder and the shield will all three coincide. An exercise sheet, as described above, ruled to provide alternate columns of shorthand and longhand, or otherwise as required, is then

inserted into the shield so that the right hand edge of the shield coincides with the left hand edge of the first column on the sheet. The shorthand outlines are then copied into the first column of the sheet, the pupil studying and analyzing the outlines as he writes, by reference to the longhand key which is side by side with the copy. Having filled the first column, the copy-holder is turned back upon its hinge so that the copy is turned face downward under the holder and thus concealed from view. The pupil then transcribes his notes which he has written in the first column, into longhand in the second column, said transcript to appear the same as the original longhand key. The copy-holder is then turned forward to its original position, exposing the copy, and the pupil then compares his transcript with the original key and makes corrections. The holder is then again reversed, concealing the copy, and the sheet is pushed into the shield far enough to conceal the first column already filled with shorthand so that nothing is exposed except his longhand transcript, from which he re-writes the exercise in shorthand in the third column. The holder is then turned forward again to expose the copy, and the pupil then compares his shorthand notes just written with the original shorthand copy and makes corrections. The holder is again reversed and the exercise again transcribed from his last notes into longhand in the next column. This process is repeated in the same routine column by column until the sheet is filled, care being taken to push the sheet into the shield after each column sufficient to cover and conceal what has already been written and expose only the column last written. It will be noted that in doing this the column last written is always side by side with the original copy when the holder is turned forward, which makes the work of comparison and correction very easy and handy.

By using two contiguous shorthand columns alternating with one longhand column, the pupil may be required, after correcting a column of shorthand, to re-write the exercise thus corrected in the adjoining column before making the next longhand transcript, thus providing himself with a perfect shorthand copy from which to make the transcript, and also furnishing twice as much practice in the writing of the exercise as

in its transcription, which proportion usually accomplishes the best results. If the pupil is found to have considerable difficulty in reading his shorthand, two contiguous longhand columns may also be provided for the rewriting of the longhand transcript in the same manner after correction. 60

The device may be used substantially in the manner described above in teaching foreign languages, spelling, scientific nomenclature, or any other subject requiring repetition study or practice for the memorizing of lists of words or terms, definitions, abbreviations, symbols, phrases or sentences, or their transcript, translation, or transposition. 65 70

Other modifications in detail may be resorted to without departing from the spirit of the invention or sacrificing any of its advantages. 75

What is claimed as new is:—

1. A device for the purpose described, comprising a box-like shield open at the end, a copy holder movably connected therewith to lie flat thereupon and to be folded away from the open end of the shield, clips on said copy holder, an exercise sheet removably contained within said shield and a backing for said sheet, and means for securing said sheet and back together. 80 85

2. A device for the purpose described, comprising a box-like shield open at the end, a copy holder movably connected therewith to lie flat thereupon and to be folded away from the open end of the shield, clips on said copy holder, an exercise sheet removably contained within said shield, a backing for said sheet, and a clip for securing the ends of said sheet and backing together. 90

3. The device herein described, comprising an exercise sheet, a backing, means for detachably holding the sheet and backing together at one end, a shield of box-like form open at one end, a cover for said shield, a copy holder hinged at one edge to said cover and adapted to fold flat against the cover or flat against the exercise sheet, and clips on the sides of said copy holder, all as and for the purpose set forth. 95 100

In testimony whereof I affix my signature, 105 in presence of two witnesses.

ROY STANLEY ASHTON.
